TOOL FOR HEATING TUBING AND THE LIKE

Josef U. Berkl, Redondo Beach, and Dee Lane Jenner, La Canada, Calif., assignors to Hi-Shear Corporation, Torrance, Calif., a corporation of California

Filed June 2, 1967, Ser. No. 7,342

Term of patent 14 years

Int. Cl. D8—02

U.S. Cl. D54—13

FIG. 1 is a side view of a tool for heating tubing and the like embodying our new design;

FIG. 2 is a top perspective view thereof;

FIG. 3 is a front elevational view thereof;

FIG. 4 is a perspective view of the side opposite that shown in FIG. 1.

We claim:

The ornamental design for a tool for heating tubing and the like, as shown and described.
